(57) **CLAIM**

The ornamental design for a laser projector, as shown and described.

DESCRIPTION

FIG. 1 is a perspective view of a laser projector showing the new design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof; and,

FIG. 9 is a partial enlarged view of the indicated area "A" in FIG. 1.

The broken lines depict portions of a laser projector in which the design is embodied that form no part of the claimed design.

The broken lines indicating an enlargement portion of the design form no part of the claimed design.
